ATTORNEY

UNITED STATES PATENT OFFICE.

CONRAD THYSSEN, OF AACHEN, GERMANY, ASSIGNOR TO RHEINISCHE METALL-
WARENFABRIK GEBR. SCHUMACHER G. M. B. H., OF AACHEN, GERMANY.

VICE.

1,389,568.

Specification of Letters Patent. Patented Aug. 30, 1921.

Application filed April 11, 1921. Serial No. 460,475.

To all whom it may concern:

Be it known that I, CONRAD THYSSEN, a citizen of Germany, residing at Aachen, No. 139 Eupenerstrasse, Rhenish Prussia, Germany, have invented certain new and useful Improvements in Vises, (for which I have filed application in Germany, November 3, 1919, No. R. 48,745 IX/87 a, filed by the Rheinische Metallwarenfabrik Gebr.

10 Schumacher G. m. b. H.); and I do hereby declare the following to be a full, clear, and exact description of the invention, such as will enable others skilled in the art to which it appertains to make and use the same.

15 My invention relates to vises, and particularly, to vises having a stationary front jaw and a rear jaw movable parallelly with relation to the front jaw.

20 The invention has for its object to provide a vise of the character stated in which the guiding and adjusting means are effectively protected against the penetration of filings or file dust into them.

25 Another object of the invention is to provide a vise which is simple in construction and the guiding means of which effectively prevent rotation of the movable jaw.

In the drawings:

30 Figure 1 is a longitudinal section of a vise constructed in accordance with my invention, and

Fig. 2 is a cross-section of the same, taken on the line A—B of Fig. 1.

35 Referring now to the drawings, 1 designates the stationary front jaw body which may be fixedly attached to a work-bench or the like and 2 is the movable rear jaw body. The stationary jaw 1 forms a central longitudinal bushing 3 having a long bore 4. Extending into the bore 4 is a tubular guiding rod or sleeve 5 which is rigidly mounted in the movable jaw 2. The sleeve 5 is provided at one end with internal screw threads designed to match the

40 threads of the ordinary adjusting screw 6 which is rotatably mounted in the stationary jaw body 1. The adjusting screw is actuated and held against longitudinal movement in any well-known manner. The inner side of the bushing 3 is smooth and forms slideways for effectively and accurately guiding the sleeve 5 and the mov-

able jaw 2 which carries the sleeve. The bushing 3 with its bore 4 extends relatively far below the rear jaw 2, that means the 55 rear jaw body 2 projects over the bushing 3 like a protecting hood to such an extent that even in wide-open position of the vise that portion of the sleeve 5 which is withdrawn from the bore 4 as well as the mouth 60 of the bore 4 are constantly covered by the movable jaw body so that no filings can fall onto the sleeve 5 or penetrate into the bore 4. Between the movable jaw 2 serving as protecting hood and the bushing 3 there 65 are no guiding parts but only a free space 7. Filings or file dust penetrating into said free space will not cause any disturbance to the vise. In order to secure an effective and accurate guiding of the jaws 70 with relation to each other, the sleeve 5 carried by the movable jaw 2 is preferably made of such length as to project beyond the vertical plane of the gripping face of the jaw 2 (seen in the direction to the left, 75 Fig. 1).

The rear jaw 2 is provided at both sides with downwardly directed longitudinal wings 8, the lower horizontal edges of which form smooth gliding faces resting on cor. 80 responding supporting faces 9 formed at both sides of the rear portion of the stationary front jaw 1. The faces 8 which aid in the proper guiding, at the same time prevent rotation of the movable jaw when 85 same is adjusted. They are smooth so that dust or other impurities will not adhere to or accumulate on the same. The supporting faces 8 are preferably arranged so far in the rear of the vise proper that they 90 remain covered and protected by the wings of movable jaw 2 even when the vise is in its extreme open position.

Having thus described my invention, what I claim as new and desire to secure by Let- 95 sert Patent, is:

In a vise comprising a stationary front jaw and a relatively movable rear jaw, a central longitudinal bushing formed by the front jaw, a guiding sleeve rigidly mounted 100 in the rear jaw and shiftably extending into the bore of said bushing, an adjusting screw rotatably mounted in the front jaw, internal threads in the said sleeve adapted to match

the threads of the adjusting screw, said bushing projecting for a relatively large extent below the movable jaw so as to be covered by the same, downwardly directed longitudinal wings formed at both sides of the movable jaw, the lower edges of said wings gliding on and covering corresponding smooth supporting faces formed at both sides of the rear portion of the stationary front jaw, and said coöperating faces adapted to aid in the guiding of the movable jaw and acting to prevent the latter from rotation when being adjusted.

In testimony whereof I have signed my name to this specification.

CONRAD THYSSEN.
